OPEN SIDE CLEVIS

Andrew A. Hocher, Etna, Pa., assignor to Hubbard and Company, a corporation of Pennsylvania

Application August 6, 1940, Serial No. 351,602

16 Claims (Cl. 24—115)

The present invention relates to clevises, and more particularly to thimble-type clevises adapted for the dead-ending of insulated lines to suspension insulators.

Clevises of the general type herein set forth have been heretofore known and extensively employed for dead-ending and other types of service. Insofar as I am aware, however, such clevises have had certain objectionable features, particularly with respect to undue wearing or abrading action on the insulated lines, cables, etc., employed therewith and/or on the insulation thereof. This is due, at least in large part, to the fact that these clevises as previously produced inevitably contained surface roughnesses and irregularities which, constantly rubbing against the line, cable, etc., weakened the same to such an extent as to shorten its life unduly, make it useless or dangerous or actually to cause the same to break. The loss of insulation also caused electrical difficulties as will be appreciated.

While it has been recognized that such surface roughnesses did exist and were objectionable, no satisfactory means of overcoming the same has been proposed. The clevises are made in large numbers and it would, therefore, be totally impracticable to attempt to finish the same by any buffing, smoothing or similar operation, not only because this would be expensive and time-consuming but because such would adversely affect the galvanizing or other protective coating with which the clevises are usually provided.

One of the main objects of the present invention is to produce a clevis which is free from the objections of prior clevises and which has further advantages peculiar to itself.

Another object of the invention resides in forming dead-ending clevises and clevises of that type out of pressed steel so as to produce a product substantially free from surface roughnesses and irregularities, thus providing a clevis which, in effect, lengthens the useful life of insulated lines, cables, etc.

A further object of the invention is to produce an open side clevis which has new and highly advantageous structural and physical properties and characteristics and which, therefore, constituted a definite advance in this art.

Other and further objects and advantages will be appreciated by those skilled in this art or will be understood or pointed out hereinafter.

In the accompanying drawings, in which like numerals designate corresponding parts:

Figure 1 is a perspective view of an open side

clevis responding to my present invention and constituting a desirable embodiment thereof;

Fig. 1a is a reduced plan view of the clevis of Fig. 1 from the opposite side thereof;

Fig. 2 is an end elevational view of the clevis of Fig. 1;

Fig. 3 is an edge view partly in elevation and partly in section of the clevis of Figs. 1 and 2;

Fig. 4 is a plan view of a modified form of 10 clevis;

Fig. 5 is an edge view of the clevis of Fig. 4;

Fig. 6 is a plan view of another modified form of clevis;

Fig. 7 is an end view of the clevis thimble of 15 Fig. 6;

Fig. 8 is a fragmentary detail of the clevis support prior to assembly;

Fig. 9 is a plan view of a further modified form of the invention;

Fig. 10 is a plan view of still another modified form of the invention;

Fig. 11 is an edge view of the clevis of Fig. 10;

Fig. 12 is an end elevational view, partly in section, of the clevis of Figs. 10 and 11 and taken 25 on line XII—XII of Fig. 11;

Fig. 13 is a plan view of a further modification of the invention;

Fig. 14 is a plan view of a still further modification of the invention;

Fig. 15 is a plan view of an additional form of clevis responding to my present invention; and

Fig. 16 is a plan view of still another form of clevis in accordance with my present invention.

Clevises of the type herein involved are especially useful for dead-ending insulated lines, cables, conductors, etc., to suspension insulators and are most commonly mounted so as to connect directly to an insulator stud. The particular form of insulator and its mounting is immaterial to the present invention and does not per se form a part hereof. Clevises of the kind here described may also be employed for other, similar or analogous purposes and, therefore, it is to be understood that the present invention is not

restricted solely to dead-ending clevises. They may, for example, be used as angular direction changers for cables, conductors, insulated lines and the like and may be mounted upon poles, cross arms, buildings or other supports, depending upon the particular requirements for any given type or kind of service.

All the forms of clevis forming a part of the present invention are composed of pressed steel, preferably galvanized or otherwise provided with a protective coating to lessen or obviate corro-

sion and surface deterioration. Pressed steel clevises are characterized by the fact that they are free or substantially free of surface roughnesses such as those so often encountered in connection with cast clevises or clevises made from other materials and/or by other procedures than by forming from pressed steel. Pressed steel clevises as here described are characterized further by great strength and resistance to the various strains to which these products are subjected during their normal use. Pressed steel clevises are less apt to become deformed by or give way under such stresses and are generally capable of withstanding higher or greater stresses for longer periods of time than other types of clevises. Pressed steel clevises of the present character are, therefore, capable of being used under conditions which make impracticable or preclude the use of the older forms of clevises. Their service, in any event, is materially longer and more efficient.

The various forms of clevis herein described and claimed are also characterized by the fact that they are composed of two main parts, herein for convenience termed a thimble and a support. The term thimble is used to designate the circular or substantially circular part of the clevis, and the term support is employed to designate the member or members which form a connection between the thimble and an insulator or other member to which the same is or may be attached. The thimble and support are connected to each other as will be hereinafter set forth.

Referring first to Figs. 1 to 3, inclusive, in detail, it will be observed that the thimble 10 is substantially concavo-convex or U-shaped in cross section, concave side outward, and extends throughout the major part of a full circle of 360°. This thimble is characterized by smooth surfaces and lack of sharp bends, angles, corners, etc., and, therefore, is well adapted to carry out the objects and purposes hereinabove outlined. Thus too when protectively coated the ultimate article is correspondingly free since most coatings faithfully reproduce underlying irregularities. The thimble is preferably—although not necessarily—made in one piece which, as shown, is formed with two radially inwardly projecting lugs 11 which form the termini of the adjacent ends of the thimble connecting with the body 10 thereof by the transition portions 12.

As will be more fully understood from Figs. 2 and 3 taken together, the distal, right-angularly extending ends 11' of the lugs 11 extend through an opening 13 in the saddle portion 14 of the support member 15, being spread outwardly, cotter-pin fashion, to maintain and lock them in position. The thimble member 10 as a U-shaped cut-away portion 16 in one edge thereof substantially diametrically opposite the lugs 11 for a purpose to be hereinafter explained.

The support member 15 is likewise preferably, although not necessarily, made in one piece and is a pressed steel stamping or pressing like the thimble portion 10 already described. The support member has a saddle portion 14 which unitarily connects a substantial proportion of the adjacent edges of the arcuate arms 17, one end of each of which is provided with an opening 18 by means of which the arms are adapted to be connected to an insulator or other member (not shown) through the medium of suitable fastening instrumentalities such as the bolt 19 and cotter-pin 20. As will be noted from Fig. 3 in particular, the arms 17 are semi-circular in general con-

figuration and somewhat converge from bolt 19 to lugs 11. They are provided with an extending tapered seat portion 21 which contacts with the side of the thimble 10 and which has a portion 22 thereof peened or otherwise forced or bent over into the U-shaped cut-away portion 16 hereinabove mentioned. This provides a firm seat and an interlock between the two members. The connection may be supplemented by spot welding or any other welding or uniting operation.

As already indicated, the lugs 11 extend through an aperture 13 in the saddle portion 14 of the support member 15 and are bent outwardly (see Figs. 1a and 2) to lock the thimble and support members together and thus the two stated members are connected at diametrically opposite points of the thimble member 10, producing an unusually strong and strain-resistant device which is structurally and functionally superior to any prior clevis, so far as I am aware. For purposes of even further strengthening the device and where there is no objection to a permanent assembly, I point out that welding may be resorted to at all points of contact such as where the arms abut the convex side of the thimble and where the lugs meet the arm ends and saddle. Optionally, I may solder or employ other modes of increasing the areas of contact and strengthening the connections as will be understood by those skilled in this art wherever such is desired.

In Fig. 1 it will be noted that I have illustrated in dotted lines the position of a conductor, cable, etc. 23 when applied to my new clevis, and one end of this member 23 may be suitably secured to the member adjacent the clevis by a suitable dead-end clamp or the like 24, the particular details of which are not a part of the present invention since any suitable form of clamp will be satisfactory. In the illustration I have shown two plates 24a grooved on their adjacent faces for the reception of the member 23 and bolted together at 24b.

The form of the invention illustrated in Figs. 1 to 3, inclusive, has been found by me to answer admirably the objects and purposes of this invention, but it is to be understood that the same is exemplary and not restrictive since within the spirit and scope hereof other specific forms of the invention may be devised without departing from the principles involved. In Figs. 4 to 16, inclusive, I have illustrated several further examples of clevises which differ in details from the embodiment of Figs. 1 to 3. In order that the invention may be more fully appreciated, I now describe in some detail several modifications of the invention which exemplify the versatility and range of application of that invention.

Referring to Figs. 4 and 5, it will be understood that the form of the invention there illustrated differs primarily from the clevis of Fig. 1 in that the projecting lugs 11a of the thimble 10a project laterally outwardly rather than radially inwardly. The saddle portion 14a of the support member 15a is longer and more tapered and projects somewhat beyond the thimble 10a so that the aperture 13a in such saddle portion registers with the said lugs 11a, the distal ends of which are bent outwardly or over the material of the saddle portion (cotter-pin fashion) so as to provide a joint or connection of the same type as in Fig. 1 but in a different location. Otherwise this form of the invention is substantially identical with that of Fig. 1, as will be noted from the use of the same numerals, but due to the differences in the locations of certain of the parts more or

greater space is provided interiorly of the thimble 10a and thus for some purposes serves where the clevis of Fig. 1 might not meet spatial requirements. As in Fig. 1, the tapered end 21 of the saddle portion of the support member 15a may be spot welded or otherwise suitably secured to the thimble 10a.

The modification of Figs. 6 to 8, inclusive, differs from Fig. 1 chiefly in the manner of connecting the thimble 10b to the support member 15b. In this particular case the thimble is a substantially complete circle of 360° and the same is slotted at 25 and 26 adjacent the point where the ends of the thimble abut. The saddle portion 14b of the support member 15b is provided at one end with the initially straight but somewhat converging lugs 11b, the balance of the support member being substantially as already described. In assembling this form of clevis, the lugs 11b are inserted into the slots 25, 26 and then peened over underneath or otherwise bent, deformed or pressed inwardly or together as shown at 11b' in Fig. 6 so as to provide a secure interlock. This form of invention has advantages which will be appreciated, particularly as to simplicity and ease of assembly and disassembly. The bent-over lugs may, if desired, be additionally secured by spot welding, soldering or in any other suitable way.

In Fig. 9 I have illustrated a very simple form of the invention wherein the thimble 10c is a perfect circle, the ends 10c' abutting in such manner as to produce a member extending a full 360°. The saddle portion 14c of the support member 15c is cut off substantially at right angles to its axis to provide an abutting end portion 14c' which fits snugly against the inner (convex) surface of the thimble at a point opposite the point of attachment of the tapered part 21, which is the same as already described. Where portion 14c' abuts the surface of the thimble, the parts are preferably suitably welded together and it is to be noted that this joint or connection overlaps the abutting ends of the thimble itself, which may and preferably is likewise welded to produce an unusually simple but extremely strong and effective clevis.

Figs. 10, 11 and 12 illustrate a clevis wherein ready accessibility for disassembly and repair is provided. In this form of clevis the thimble 10d is somewhat less than 360° as shown so that the adjacent ends 10d' of the thimble 10d are somewhat spaced apart. The material of the thimble is struck up on the inner convex side thereof at points adjacent each such end 10d' so as to provide a pair of pockets or passages 10d'' through which the angularly out-turned lugs 11d of the support member 15d are disposed. The extreme ends of these lugs are turned upwardly and inwardly (see Fig. 10) after assembly, thereby providing a simple but effective interlock which provides for service under conditions somewhat different from the other clevises so far described. In Fig. 10 also it will be observed that the tapered end 21d of saddle portion 14d projects through a U-shaped struck-up portion 16d in the side of the diametrically opposite portion of thimble member 10d. The extreme end may or may not be turned downwardly and/or inwardly to increase the interlocking effect, depending upon the desirability of ready disassembly. Figs. 11 and 12 aid in an understanding of the disposition and relationship of the parts which otherwise are like those of Fig. 1.

In Fig. 13 the arrangement is somewhat sim-

ilar to Fig. 10 but the lugs 11e of the saddle portion 14e of the support member 15e are riveted at 11e' to the adjacent (spaced) ends of the thimble 10e, and hence do not require the provision of the struck-up portions 10d'' characteristic of the clevis of Fig. 10. Likewise the clevis of Fig. 13 avoids the necessity for further turning or bending operations on the lugs as well as eliminating the necessity for the striking-up operation itself. In this clevis the saddle portion 14e of the support member 15e is shown as being somewhat wider and sturdier, and the end surfaces 10e' of the spaced thimble ends are shown as being parallel instead of divergent as in Fig. 10. The tapered end 21e of the saddle portion is like that of Fig. 1.

Fig. 14 illustrates a variant of the clevis of Fig. 13 and for certain or special purposes is preferable. In Fig. 14 the thimble 10f is of D-shape, although the ends 10f' of this modified thimble are spaced as in Fig. 13. The lugs 11f of the shortened saddle portion 14f are welded to the flattened surface of the inner portion of the D-shaped thimble as shown. It is, of course, to be understood that instead of welding rivets may be employed as in Fig. 13, in which connection also the welded connection of Fig. 14 may be equally well employed in place of the rivets of Fig. 13 in the latter structure. The clevis of Fig. 14 has somewhat different proportions and stress resistances, but basically is the same as the other forms of clevis herein described.

Fig. 15 illustrates a further modified form of clevis in which the extreme (spaced) ends 10g' of the thimble 10g are provided with struck-up portions 10g'' similar to those designated at 10d'' in Fig. 10, although both the position and the actual structural arrangement is appreciably different as will be noted. The saddle portion 14g of the support member 15g is provided at one end with two opposed L-shaped lugs 14g' which, when the support member is first produced, extend out at an angle to the support member, as will be apparent. In assembling this form of clevis, the lugs 14g' are forced toward each other through short arcuate paths until they project through the struck-up end portions 10g'' to assume the ultimate (full line) position illustrated in Fig. 15, it being understood that the extreme ends may be bent over either upwardly or downwardly to increase the effectiveness of the interlock if so desired.

The opposite end 21g of the saddle portion 14g may either be as in Figs. 1 to 9, inclusive, or the more pronouncedly triangular end of such member may be more or less countersunk in a corresponding depression or cut-away portion 16g in the side of the clevis thimble diametrically opposite to the struck-up portions 10g'' aforesaid, it being understood that no undue weakening of the thimble is thereby effected nor is the recessing or cutting out of such nature as would in any sense result in a two-piece thimble. The other parts are substantially as previously described.

Finally, in Fig. 16 I have illustrated a clevis in which the more or less U-shaped terminal lugs 11h on one end of the saddle portion 14h of support member 15h project upwardly through slots or apertures 27 provided in the convex portion of the thimble 10h adjacent the slightly inturned or offset spaced ends of such thimble. It will be understood that initially the lugs 11h may be straight as indicated at 11h' but that for assembly and interlocking purposes the same are bent into the U-shape shown and described. The tab-

like reduced end $21h$ of the saddle portion $14h$ of support member $15h$ projects through a struck-up portion $16h$ on the side of the thimble in a manner similar to portions $16d$ of Figs. 10 and 11. Otherwise the parts are the same as previously described.

One or more of the above clevises is capable of satisfactorily solving any problem which may arise in connection with the employment of a clevis of the general type herein described. The particular form employed in any particular set-up depends upon the circumstances involved in a particular installation. The clevises described lend themselves to inexpensive production, to long and satisfactory operation and to freedom from failures and difficulties encountered in connection with the use of prior clevises. The clevises herein described and claimed are all characterized by the fact that they are made of pressed steel and are therefore smooth and unusually free of any surface irregularities which might cause undue wear or deterioration to the conductors, cables and the like members contacting therewith, especially in connection with insulated members, in which connection the insulation is not destroyed or removed prematurely when any one of my present clevises is utilized.

In setting forth the above embodiments of my invention, it is to be understood that I may make other and further omissions, additions, substitutions and alterations within the scope of the appended claims, which are rather deemed to define the metes and bounds of my present invention. While I have described the various clevises as being made of pressed steel, I am not limited as to the particular composition or analysis of that material as it is clear that a wide variety thereof may actually be used, depending upon factors well understood in this field such as cost, appearance, resistance to corrosion and longevity. Any or all such materials may be suitably coated as by galvanizing operations, although it is to be understood that any approved corrosion- and abrasion-resistant coating may be employed whether of a metallic or non-metallic nature, in which latter connection suitable enamels, plastics or paint-like compositions can be employed. The expression open side clevis as used in the claims is intended to cover all the products hereinbefore described as well as the various modifications thereof which fall within the purview hereof.

Having thus described my invention, what I claim as new and desire to secure by Letters Patent is:

1. A clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, said thimble being provided with a pair of lugs which are adapted to pass through an aperture provided for that purpose in the contiguous portion of said support member.

2. A clevis of the character described which comprises a thimble of concavo-convex section with its annular groove on the outside, a support member contacting with said thimble at a plurality of spaced points and adapted for connection to an operatively associable member

and means for securing said support member to said thimble at the contact points to produce a clevis which will withstand strains to which it may be subjected during use, said support member being provided with lugs adapted to pass through openings formed in the contiguous portion of said thimble.

3. A pressed steel clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, said thimble and support member being provided with cooperating portions which form a mechanical interlock therebetween.

4. A clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, said means including parts on said thimble and support member for mechanically interlocking the same together.

5. A clevis of the character defined by claim 1 in which said lugs extend radially inwardly from the convex surface of said thimble and are connected to the thimble by means of tapered transition portions.

6. A clevis of the character defined by claim 1 in which the lugs extend laterally outwardly from the side of the thimble.

7. A clevis of the character defined by claim 3 in which the mechanical interlock includes a pair of spaced apertures in the convex side of said thimble and a pair of lugs extending from the adjacent end of said support member through said apertures, the ends of the said lugs being deformed to prevent withdrawal from the apertures.

8. A clevis of the character defined by claim 3 in which the mechanical interlock includes a plurality of spaced struck-up portions on the convex side of said thimble and an equal number of lugs on the adjacent end of the support member extending through said struck-up portions and being deformed therebeyond to prevent withdrawal therefrom.

9. A clevis of the character defined by claim 3 in which the mechanical interlock includes a pair of apertured enlargements on the adjacent spaced ends of said thimble and a pair of L-shaped lugs the free ends of which extend through the said apertures.

10. A clevis of the character defined by claim 3 in which the mechanical interlock includes a pair of spaced openings in the adjacent spaced ends of said thimble and a pair of initially straight U-shaped lugs on the contiguous end of said support member and interlocking with said thimble via said openings.

11. A pressed steel clevis of the character described which comprises a thimble of concavo-convex section with its annular groove on the outside, a support member contacting with said thimble at a plurality of spaced points and adapt-

ed for connection to an operatively associable member and means for securing said support member to said thimble at the contact points to produce a clevis which will withstand strains to which it may be subjected during use, the said thimble being substantially in the form of an annulus and being split at a point substantially in alignment with said contact points.

12. A pressed steel clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, the said thimble being substantially in the form of an annulus and being split at a point substantially in alignment with said contact points, the ends of the said annulus at the split being in abutting relationship.

13. A pressed steel clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, the said thimble being substantially in the form of an annulus and being split at a point substantially in alignment with said contact points, the ends of the said annulus adjacent the split being spaced apart and out of contact with each other.

14. A pressed steel clevis of the character described which comprises a thimble of concavo- 40

convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, the said thimble being of substantially D-shape.

15. A pressed steel clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, the said thimble being provided with a U-shaped cut-away portion at one of the said points of contact with said support member in which a tapered extension on said support member is adapted to be received.

20 16. A pressed steel clevis of the character described which comprises a thimble of concavo-convex section with its annular groove on the outside, a support member contacting with said thimble at a plurality of spaced points and adapted for connection to an operatively associable member and means for securing said support member to said thimble at the contact points to produce a clevis which will withstand strains to which it may be subjected during use, said support member being provided with a tapered extension and said thimble being provided with portions adapted to cooperate therewith for interlocking purposes.

ANDREW A. HOCHER.

CERTIFICATE OF CORRECTION.

Patent No. 2,252,566.

August 12, 1941.

ANDREW A. HOCHER.

It is hereby certified that error appears in the printed specification of the above numbered patent requiring correction as follows: Page 2, first column, line 58, for "as" read --has--; and that the said Letters Patent should be read with this correction therein that the same may conform to the record of the case in the Patent Office.

Signed and sealed this 23rd day of September, A. D. 1941.

(Seal)

Henry Van Arsdale,
Acting Commissioner of Patents.
